TWO PIECE CARTRIDGE AND METHOD OF
MAKING SAME

Everett F. Stealey, Cleveland, Ohio, assignor to The Boehm Pressed Steel Company, Cleveland, Ohio, a corporation of Ohio

Application May 27, 1955, Serial No. 511,595

5 Claims. (Cl. 102—44)

This invention relates to methods and means for making two-piece steel cartridge cases and the objects of this invention are the same as recited in my copending but now abandoned application Serial No. 499,648, filed April 6, 1955, but with the addition of certain changes in construction representing an important modification of the aforesaid pending application.

An important object of the present invention over the pending application is the provision of an improved construction for connecting a wrap-around case with the base which restrains too great an expansion of the case under the force of the exploding charge as will make rapid ejection of the shell from the breech difficult under some conditions. In other words, the present connection of the case with the base offers a joint which will yield to a degree and permit only so much case expansion as will assure a gas-tight seal in the breech under fire, and yet will recover or return to its original diameter to make certain of positive and rapid ejection, the proof of this being evidenced by the fact that the case can be re-chambered without effort.

Another important object is the provision of a wrap-around case with a base fastening flange which is substantially parallel with the axis of the shell and normal to the adjacent most yieldable free or spring-like portion of the case, so that the juncture of the flange with the spring-like portion can be subjected to a controlled restraining pressure offered by the base locking rib sufficient to allow ejection of the assembly without separation of the base and case and, at the same time, permitting natural orientation of the laminations of the flange.

Like the aforesaid pending application, the present invention provides for case expansion and contraction of the laminated wrap-around case and flange by reason of a portion of the laminated flange being supported upon the base and exposed to pressures within the case with freedom of its laminations to move or adjust during winding or unwinding tendencies of the case caused by applied and residual stresses. The axial component of an exploding charge within the case expands it against the breech walls and against the base to preclude possibility of gas leakage from within and around the case.

Other objects and advantages of the invention will become apparent during the course of the following description.

In the accompanying drawing forming a part of the description wherein like numerals are employed to designate like parts throughout the several views:

Figure 1 is a vertical section taken through the center of the improved base showing the improved case connected therewith;

Figure 2 is an enlarged section of one side of the joint between the case and base showing the relative position of the parts prior to firing or exploding the shell;

Figure 3 is a similar view showing the relative positions of the parts after firing for explosion of the shell; and

Figure 4 is an enlarged section of one side of a modified joint between the case and base prior to firing.

2

Referring more particularly to the drawing, the numeral 10 designates a cylindrical body shell, or case, of low carbon steel formed by rolling a trapezoidal shaped sheet into cylindrical form to provide what is termed a "wrap-around" type of cartridge case. The sheet being rolled or wound spirally provides the case with plural coiled spring-like laminations or layers. With this type of case, internal pressure tends to unwind the resilient coil formation of the body structure until contact is made with the breech wall. In contrast to the drawn steel case, in which the wall of the body is subjected to hoop tension, which condition induces high stresses often exceeding the yield point of the material and causing permanent deformation, the coiled spring-like formation of the "wrap-around" case is subjected, in the main, to bending strains which are quickly reversed on subsidence of pressure.

The end of the laminated case 10 which is connected to the base plate 11 is shown in the drawings with the tapered end of the blank or inner convolution designated at 12 and the other tapered end of the trapezoidal blank or outer convolution designated by the dotted line 13. This cylindrical body shell is, of course, placed under pressure on a mandrel to iron the spirally disposed edges of the blank into a true cylindrical form without raised portions on the inner and outer surfaces of the body shell as is well understood in the art. This laminated end of the case is formed to include a first inwardly extending conical flange portion 14 adjacent the cylindrical body wall of the case, an intermediate flange portion 15 which is substantially normal to the case axis, and a second flange portion 16 substantially normal to the intermediate portion 15 and substantially parallel with the case axis. The portions 15 and 16 meet at a corner or juncture portion 17. The resilient laminated portions 14 and 15 of the case are supported upon the base 11 and are free to move relatively and relative thereto either in firing or in storage. These portions of the case constitute a stepped flexible flange portion which is free to expand and contract radially and circumferentially and to move axially relative to the base plate.

The base plate 11 for the cartridge case is preferably made from low cost carbon steel with a contoured face having a first conical surface 18 adjacent the periphery of the base to seat and support the outer surface of the conical flange portion 14 of the case, a second surface 19 concentric with the surface 18 and substantially parallel with the end surface 20 of the base to seat and support the outer surface of the intermediate flange portion 15. Spaced a substantial distance inwardly from the periphery 25 of the base and the intermediate surface 15 and concentric therewith, the base is provided with an annular groove 21. This groove is just slightly deeper than the flange 16 is long and is slightly wider than the combined thickness of the laminations of the flange. The base plate 11 in all modifications shown herein is cold coined as in my copending application Serial No. 389,774, now U. S. Patent No. 2,818,021, to increase its physicals and the finish of the entire surface of the base including the supporting surfaces 18 and 19. This coining compacts or compresses the fibres of the base and of the rib 25 to be presently described. The outer wall 22 of the groove 21 is substantially perpendicular to the surface 19 to meet the same at a substantial right angle corner 23 preferably having a radius of about one-sixteenth of an inch. The inner wall 24 of this groove extends a distance beyond the surface 19 to provide one side of an annular upstanding rib 25 which is sufficiently large and has an inclined face 26 against which pressure is exerted to deform the rib and cause it to span the groove and squeeze or pinch the juncture 17 of the case flange portions 15 and 16 against the corner 23 to retain the flange 16 within the groove 21.

After this deformation of the rib, it may be staked as at 30 at an angle of about forty-five degrees as shown in Figure 4 to further compress the juncture portion 17 of the case against this corner 23. Pressure exerted upon the rib in fastening the case flange within the groove 21 pinches the juncture portion 17 over the corner 23 to a degree which may cause a slight reduction in the thickness of the case laminations at this point. This may also cause the laminations of the flange 16 within the groove to angle at about five degrees, which is permitted by the groove being wider than the combined thicknesses of the flange laminations as shown in Figure 2. If desired, the flange 16 as shown in Figure 4, instead of being formed parallel with the case axis, may be initially inclined slightly inward at about a five degree angle relative to the case axis to make it somewhat of a conical shape, but not to the extent shown in my copending application, wherein there is more of a tendency for the end conical flange to pull radially out of the groove upon firing. By extending the flange 16 parallel with the case axis, with controlled confinement of said flange within a groove of slightly greater width than flange thickness, a small amount of unwinding of the flange laminations is provided for.

Figure 4 illustrates a modification of the connection between the case 10 and base 11 and here the parts which correspond to those of the preceding modifications are designated with corresponding reference numerals. The variations over the other figures are first, that the base plate of Figure 4 omits the inclined surface 18 and instead has a surface 35 which is parallel with the end face 20 to take the place of both surfaces 18 and 19 of the preceding modification. The second variation is that the case 10 is provided with a free flange portion 15' normal to the case axis and corresponds with the portion 15 of the preceding modification.

Just exactly what changes occur in the positions of the parts at the instant of firing is not known; but as far as can be discerned after firing the shell and sectioning or cutting the same transversely or removing a pie-shaped segment thereof, it is noted that the outer lamination 27 of the flange portion 14 and the intermediate lamination 28 has been driven down hard against the base 11, while the inner lamination 29 and the outer portion of the intermediate lamination 28 of the flange portions 14 and 15 has heaved inwardly in spaced relation to the other convolutions, probably due to the uncoiling tendency of the wrap-around case during the explosion and the recoil tendency of the case to return to normal position immediately after the explosion. It is believed that this flexibility of the case in these regions of free movement of the portions 14 and 15 allows the case to literally breathe to expand to the breech walls under fire, or in storage, and to retract under residual stress to return toward its original diameter for easy ejection.

It is also unknown exactly what action occurs in the flange 16 within the groove 21 at the instant of firing or applied stress. However, after firing and sectioning of the shell, it appears that there has been a relative slight slippage lengthwise between the laminations of the flange 16 due to their changed positions as depicted in Figure 3 and comparing it with the original positions of the parts before firing as shown in Figure 2. It is believed that while the compression of the laminations or layers between the corner 23 of the groove and the rib 25 is great at the instant of firing, nevertheless, it is possible that there is some degree of slippage between these compressed laminations; but not anywhere near sufficient to pull the flange 16 out of its groove. Such action and construction of the joint probably allows the case to slightly unwind during firing, in varying degrees throughout its length, and permits return to a smaller diameter upon the recoil or winding action of the case permitting orientation of the laminations within the confines defining the anchorage of the case flange in its groove. Whatever may be the correct theory of operation of this shell, it has been found

from actual firing tests to meet the rigid requirements of gas tightness between the case and base, rapid chambering and ejection, with no possibility of adverse effects upon the shell from long storage.

Although this invention has been described in its preferred form with a certain degree of particularity, it is understood that the present disclosure of the preferred form has been made only by way of example and that numerous changes in the details of construction and the combination and arrangement of parts may be resorted to without departing from the spirit and the scope of the invention as hereinafter claimed.

What is claimed is:

1. A two-piece cartridge case comprising a base having a contoured inner face, said face near its periphery provided with a conical surface and a surface normal to the axis of said base positioned radially inwardly therefrom, said contoured face inwardly of said normal surface having an attaching groove forming with said normal surface a juncture corner, said base inwardly of said groove having a deformable rib adapted to be deformed toward said juncture corner, a tubular body shell formed from a sheet of material forming a "wrap-around" cylindrical case, said case having a first inwardly directed conical flange portion unattached to and supported upon said conical surface, said first flange portion having a second flange portion normal to the shell axis unattached to and supported on said normal surface of said base and exposed to an exploding charge within said shell, said conical and normal flange portions being free to move relative to said base, said second flange portion terminating in a flange parallel with the axis of said shell and having its juncture portion with said normal portion of said second flange portion confined between said juncture corner and said deformable rib, said terminal flange portion parallel with the axis of said shell being loosely received in said attaching groove, and the inner lamination of said second flange portion at its conical and normal portions being free to move relative to its other laminations to compensate for strains resulting from residual and applied stresses.
2. A two-piece cartridge case comprising a base having a face near its periphery provided with a supporting surface substantially normal to the axis of said base, said face having spaced a substantial distance inwardly of its periphery an attaching groove forming with said surface a juncture corner, said base inwardly of said groove having a deformable rib adapted to be deformed toward said corner, a cylindrical body shell formed of plural spirally coiled resilient laminations, said shell having an end formed into a flanged portion with plural spirally coiled resilient laminations and having a first section adjacent said shell body substantially normal to said shell axis supported unattached upon said supporting surface of said base and exposed to the exploding charge of said shell and free to move relative to said base, said flange portion having a second section substantially parallel to said shell axis and having its juncture with said normal portion of said flange portion pinched between said juncture corner and said deformable rib, said second section of said flange portion being loosely received in said attaching groove, said flange portion being secured to said base only at said juncture corner, and said laminations of said flange portion being free to move relatively upon coiling and uncoiling tendencies of said body shell.
3. A two-piece cartridge case comprising a base having a supporting surface substantially normal to the axis of said base and having spaced a substantial distance inwardly of its periphery an attaching groove having side walls substantially parallel with the axis of said base, one of said side walls forming with said surface a juncture corner, the other of said side walls being extended axially beyond said surface to form a deformable rib opposite said juncture corner, a cylindrical body shell formed of plural spirally coiled resilient laminations, said shell hav-

ing an end formed into an inwardly extending flanged portion with plural resilient laminations and having a first section adjacent said body shell substantially normal to said shell axis supported unattached upon said supporting surface of said base and free to move relative to said base, said flange portion having a second section substantially parallel to said shell axis and having its juncture with said first section arranged upon said juncture corner, said deformable rib being deformed toward said corner to pinch said juncture portion of said flange between said rib and said juncture corner, said second section of said flange portion being loosely received in said attaching groove, and said laminations of said first section of said flange portion being free to move relatively upon winding and unwinding of said coiled laminations of said body shell.

4. A two-piece cartridge case comprising a base, a body shell formed of a plurality of spirally coiled resilient laminations, said body shell having an end formed into a flange portion extending axially inwardly towards the shell axis and engaging said base and a second and terminal flange portion extending substantially axially and towards said base, said base having an annular recess in which the second flange portion of the body shell is loosely received, the radially outer wall of said recess forming a juncture corner in said base, said base having a deformable annular rib pressed generally radially outwardly in the cartridge case to retain the shell laminations in tight association with each other only at a pressure zone formed by a portion of the annular rib pressing a section of the body shell flange against the juncture corner of the base.

5. A two-piece cartridge case comprising a base, a body shell formed of a plurality of coiled relatively movable laminations, said shell having an end formed into a first flange portion extending substantially normal to the shell axis but supported on said base, and a second and terminal flange portion extending substantially parallel to the shell axis and towards said base, said base having an annular recess in which the second flange portion of the body shell is received, the radially outer wall of said recess forming a juncture corner in said base, said base having a rib forcing said body shell laminations into tight association with each other and against the juncture corner of the base, the remainder of said first and second flange portions being unattached and free for relative movement and said first flange portion is free for axial movement away from said base whereby axial extraction forces applied to said base exert contractive forces on the convolutions of said body shell and may pull said first flange portion away from said base.
